(57) **CLAIM**

The ornamental design for a tire puncture repair tool, as shown and described.

DESCRIPTION

FIG. 1 is a perspective view of a tire puncture repair tool; FIG. 2 is a front view thereof, the rear view being identical to the front view;

FIG. 3 is a left side view thereof, the right side view being identical to the left side view;

FIG. 4 is a top view thereof; and,

FIG. 5 is a bottom view thereof.

The broken lines in the drawings are directed to features of the tire puncture repair tool that form no part of the claim.
